(57) **CLAIM**

We claim the ornamental design for a smart multimeter, as shown and described.

DESCRIPTION

FIG. 1 is a first perspective view of a smart multimeter showing our new design;

FIG. 2 is a second perspective view of FIG. 1, viewed in another aspect;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line showing of the environment is for illustrative purposes only and forms no part of the claimed design.
